DESIGN FOR A CHAIR

Frank A. Gaide, Boston, Mass.

Application June 23, 1944, Serial No. 114,159

Term of patent 14 years

(Cl. D15—1)

To all whom it may concern:

Be it known that I, Frank A. Gaide, a citizen of the United States, residing at Boston, in the county of Suffolk and State of Massachusetts, have invented a new, original, and ornamental Design for a Chair, of which the following is a specification, reference being had to the accompanying drawings, forming part thereof.

Figure 1 is a perspective view of a chair, showing my new design;

Figure 3 is a top plan view;

Figure 3 is a front elevational view; and

Figure 4 is a side elevational view thereof.

I claim:

The ornamental design for a chair, as shown.

FRANK A. GAIDE.
